To all whom it may concern:

Be it known that I, ERNEST H. My design is applicable to and intended for the surface ornamentation of woven rugs. In its essentials it consists, as shown in the drawing, of three rectangular rows of figures *a*, *b*, and *c* and forming three closely-con-

tiguous border-lines inclosing a field-center, 15 in which are two diamond-shaped figures *d d* and between them a scroll figure *e*, with halves *e' e'* of a like scroll figure at each end.

I claim—
